(57) **CLAIM**

The ornamental design for a bank note bundling machine, as shown and described.

DESCRIPTION

FIG. 1 is a perspective view of a bank note bundling machine;

FIG. 2 is a perspective view thereof in a state of being use;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken line showing in FIG. 2 is for illustrative purposes only and forms no part of the claimed design.
